UNITED STATES PATENT OFFICE.

EDWARD A. GEHRKE, OF LINCOLN, NEBRASKA.

BALL-COCK FOR FLUSH-TANKS.

1,110,436.

Specification of Letters Patent.

Patented Sept. 15, 1914.

Application filed September 22, 1913. Serial No. 791,065.

To all whom it may concern:

Be it known that I, EDWARD A. GEHRKE, a citizen of the United States, residing at Lincoln, in the county of Lancaster and State of Nebraska, have invented a new and useful Ball-Cock for Flush-Tanks, of which the following is a specification.

The invention relates to improvements in ball cocks for flush tanks.

10 The object of the present invention is to improve the construction of ball cocks for flush tanks, and to provide a simple and comparatively inexpensive ball cock of simple, strong and durable construction, which 15 will be quick acting and silent and adapted to be easily and quickly repaired in case of accidents.

Another object of the invention is to provide a ball cock having a straining device 20 and equipped with an efficient catch basin, adapted to drain when the main water supply is cutoff.

With these and other objects in view, the 25 invention consists in the construction and novel combination of parts hereinafter fully described, illustrated in the accompanying drawing, and pointed out in the claims here-to appended; it being understood that various changes in the form, proportion, size 30 and minor details of construction, within the scope of the claims, may be resorted to without departing from the spirit or sacrificing any of the advantages of the invention.

In the drawing:—Figure 1 is a vertical 35 sectional view of a ball cock, constructed in accordance with this invention and shown applied to a portion of a flush tank. Fig. 2 is a horizontal sectional view on the line 2—2 of Fig. 1. Fig. 3 is a vertical sectional view 40 on the line 3—3 of Fig. 2.

Like numerals of reference designate corresponding parts in all the figures of the drawing.

In the accompanying drawing in which is 45 illustrated the preferred embodiment of the invention, 1 designates a ball cock body arranged horizontally and provided at one end with a straight depending tubular discharge arm 2 and having a laterally projecting 50 downwardly extending tubular inlet arm or elbow 3, connected with the said end of the body at a point above and beyond the tubular discharge arm 2. The body 1 is provided with an interiorly arranged partition 4, extending upwardly from the outer side of the 55 discharge arm 2 to the top of the body and

separating the inlet and discharge arms and provided with a threaded opening 5, arranged concentric with the axis of the body portion 1 and receiving an exteriorly threaded tubular valve seat 6, capable of adjustment and arranged to be engaged by a heavy rubber washer 7, which is carried by a shaft 8. The tubular adjustable valve seat, which is designed to be constructed of copper 60 bronze or any other suitable material, is adapted to be made of a better and harder material than the body of the ball cock, and it thereby increases the durability of the same. The tubular valve seat is provided with opposite interior lugs or enlargements 9, adapted to be engaged by a suitable tool when the shaft 8 is removed, whereby the valve seat may be adjusted without detaching the body.

The body 1 is provided with coarse interiorly arranged screw threads 10, which are engaged by coarse exterior threads 11 formed on an enlargement 12 of the shaft 8 and adapted to produce a quick action of 65 the ball cock. The enlargement is located at an intermediate point between the ends of the shaft, which is provided at its inner end with a head 13, having a circular recess 14, to receive the heavy rubber washer 7, 70 which is secured in the recess by a screw 15. The screw 15 extends through a central opening of the washer and engages a threaded bore 16 in the inner end of the shaft 8. The outer portion of the shaft receives an inner 75 metal washer 17, which is arranged in an interior annular recess 18 at the front end of the body 1, which is provided with exterior screw threads 19 for engaging interior threads of a cap 20. The cap 20, which 80 forms a stuffing box and receives a suitable packing 21, has a central opening 20^a for the outer portion of the shaft 8 and is provided with an interior annular recess 22 located at the inner end of the interiorly 85 threaded portion of the cap and receiving a washer 23 of fiber or other suitable material. The washer 23, which is of greater diameter than the washer 17, fits against the outer 90 face of the same and extends beyond the joint, the outer washer overlapping the joint between the same and the front end of the body 1.

The outer end 24 of the shaft is rectangular in cross section and tapered to fit a correspondingly shaped polygonal opening 25 of an arm 26, secured on the tapered end 24

of the shaft 9 by a screw 27 engaging a threaded bore 28 of the said shaft. The arm 26, which is arranged at right angles to the shaft, extends therefrom and is provided at 5 its outer end with an interiorly threaded socket 29 for the reception of a rod 30 of a float 31, which is preferably in the form of a ball. The float is adapted to rise and fall in the usual manner with the water in the 10 flush tank to automatically operate the valve. No claim is made in the present application to the construction of the ball cock.

The depending discharge arm 2 is interiorly threaded to receive a relatively large 15 depending discharge pipe 32, extending downwardly to within a short distance of the bottom 33 of the flush tank. The said tubular arm 2 is also provided with an interiorly threaded lateral outlet 34 in which 20 is secured a relatively small discharge pipe 35 to furnish water for the afterflow or water seal following the flushing of the closet.

The elbow arm 3 is interiorly threaded to 25 receive the upper end of a vertical pipe or tube 36, which is interiorly threaded to receive a strainer 37, consisting of a disk of suitable straining material secured to an exteriorly threaded sleeve 38, which engages 30 the interior threads of the main pipe or tube 36. The lower end 39 of the main pipe or tube is exteriorly threaded to screw into the upper interiorly threaded end 40 of a short coupling tube or section 41, which extends 35 through the bottom 33 of the flush tank. The coupling tube or section 41 is provided with an interior annular flange 42, forming a stop for the lower end of the main vertical tube 36 and provided with a threaded opening 43 in which is mounted a short inner vertical tube 44, spaced from the interior of the main vertical tube 36 and forming an annular inner space and providing a catch basin for sediment strained by the strainer 40 37. The lower end 45 of the inner vertical tube is threaded to engage the threads of the interior flange 42, and the said tube 44 is provided at the upper face of the flange 42 with 45 a drain opening 46 for draining the catch basin when the main water supply is cutoff.

The coupling tube or section 41 projects below the bottom of the flush tank and is exteriorly threaded at 47 for the attachment of a water supply pipe 48. The coupling

tube or section is provided at the upper face 55 of the bottom 33 with an integral exterior annular flange 49 and the exterior threads of the lower portion 47 receive a threaded collar or nut 50, which coacts with the flange 49 in clamping the bottom 33 of the flush 60 tank. An elastic gasket 51 is interposed between the nut 50 and the bottom 33 of the flush tank to take care of any shrinking or swelling of the bottom when the flush tank is constructed of wood. 65

What is claimed is:—

1. In combination with a flush tank, of a coupling section piercing the bottom of the flush tank and having means for engaging the same and provided with an interior 70 flange having an opening, a main vertical tube mounted within the upper portion of the coupling section and having its upper end interiorly and exteriorly threaded, a strainer engaging the interior threads of 75 the main tube, a ball cock mounted on the upper end of the main tube and engaging the exterior threads thereof, and an inner vertical tube mounted in the opening of the said flange and extending into the lower portion of the main vertical tube and spaced therefrom to form a catch basin, said inner vertical tube being provided above the flange with a drain opening. 80

2. The combination with a flush tank, of a coupling section piercing the bottom of the flush tank and provided with means for engaging the same and having an upper projecting portion, said upper projecting portion being provided with an interior flange having 85 an opening, a main vertical tube mounted in the upper projecting portion of the coupling section and seated upon the said flange, and an inner vertical tube secured in the opening of the said flange and extending upwardly 90 into the main vertical tube and arranged in spaced relation with the same to form a catch basin, said inner vertical tube having a drain opening and the said tubes being removable from the coupling section without detaching the latter from the flush tank. 95 100

In testimony, that I claim the foregoing as my own, I have hereto affixed my signature in the presence of two witnesses.

EDWARD A. GEHRKE.
